(57) **CLAIM**

The ornamental design for a chain guide for motorcycle as shown and described.

DESCRIPTION

FIG. 1 is a left-front-top perspective view of a chain guide for motorcycle showing our new design.

FIG. 2 is a front view of the chain guide for motorcycle of FIG. 1.

FIG. 3 is a rear view of the chain guide for motorcycle of FIG. 1.

FIG. 4 is top view of the chain guide for motorcycle of FIG. 1.

FIG. 5 is a bottom view of the chain guide for motorcycle of FIG. 1.

FIG. 6 is a right side view of the chain guide for motorcycle of FIG. 1.

FIG. 7 is a left side view of the chain guide for motorcycle of FIG. 1.

FIG. 8 is a left-front-bottom perspective view of the chain guide for motorcycle of FIG. 1; and,

FIG. 9 is a right-rear-top perspective view of the chain guide for motorcycle of FIG. 1.

The broken lines in FIGS. 1-3, 5, and 7-9 illustrate unclaimed subject matter and form no part of the claimed design.

1 Claim, 9 Drawing Sheets
